UNITED STATES PATENT OFFICE.

WILBUR H. FISHER, OF OTTAWA, ILLINOIS, ASSIGNOR TO A. STEIN & COMPANY, OF CHICAGO, ILLINOIS, A CORPORATION OF ILLINOIS.

WORK HOLDER FOR SEWING MACHINES.

Application filed January 10, 1923. Serial No. 611,702.

My invention has reference to a work holder and feeding device for sewing machines, and is designed particularly to hold a pad or other article to be stitched, in a manner to permit the stitching to be applied entirely around the pad and close to the edge thereof.

In stitching pads such as in garters, hose supporters and the like, it is customary to provide a holder which operates with the sewing machine to move the pad automatically in a path corresponding to the form or outline of the stitching so that when the pad is placed in position, the machine automatically moves the pad in the proper course to effect the desired stitching.

Pad holding devices have been provided heretofore which engage the edges of the pad at the outer side of the line of stitching, and thus permit the stitching to be continued entirely around the pad. The stitching, however, cannot be applied close along the edge of the pad owing to the necessity of having sufficient material extending beyond the line of stitching to be engaged by the holder. In some cases, as for example, in garter and hose supporter pads, it is desirable to apply the stitching so close to the edge of the pad that there is not sufficient material outside the line of stitching to be engaged for holding the pad, and it has, therefore, been customary heretofore to effect the stitching of pads and other articles close to the edge by holding and feeding the pad or article by hand. With my machine, I provide means for holding the pad or article at the inside of the desired line of stitching so that the stitching may be located very close to the edge of the pad or other article, said holder being arranged so that the stitching may be continued entirely around the holder without the latter interfering with or interrupting the continuity of the enclosing or surrounding line of stitching.

The principal objects of my invention are to provide a device whereby a pad, label or other article may be stitched entirely around and close to the edge; to hold a pad, label or other article within the surrounding path of stitching so that the course of stitching of the needle is not interrupted or interfered with by the pad holding device; to provide a floating holder within a marginal frame and supported by the latter in such a manner as to afford an unobstructed

endless path between the holder and the frame; to provide an improved holder affording convenient access for applying and removing the work; and in general, to provide a simple and dependable work holder for a sewing machine whereby the work is automatically advanced to apply a line of stitching around and close to the edge of an article.

On the drawings:

Fig. 1 is a side view of a sewing machine having my invention applied thereto, some of the parts being broken away and others in section to disclose details of the construction;

Fig. 2 a top view of the pad holding and feeding mechanism in the position at the beginning of the stitching of a pad;

Fig. 3 a view similar to Fig. 2, showing the position of the parts as the presser foot ring passes from engagement with one of the spiders into engagement with the other spider;

Fig. 4 an enlarged view on the line 4—4 of Fig. 1, showing the pad clamp raised and the pad in position in the holder;

Fig. 5 a sectional view on the line 5—5 of Fig. 2, showing the latch for holding the pad clamp in the holding position;

Fig. 6 a detail view of the pad clamp with one of the spiders thereon;

Fig. 7 a sectional view on the line 7—7 of Fig. 2;

Fig. 8 a sectional view on the line 8—8 of Fig. 2; and

Fig. 9 a fragmentary sectional view on the line 9—9 of Fig. 4.

I have illustrated herein a particular embodiment of my invention for edge stitching the pads of double hose supports such as are commonly worn by men, although it is to be understood that the invention is adapted to be used for stitching pads of various sizes and shapes by making modifications which will be readily apparent to those familiar with this art. In connection with my invention, I employ automatic feeding mechanism for moving the pad in a path corresponding to the particular form of the pad which is to be stitched, so that the stitching will follow a course around the edge of the pad. Any suitable mechanism may be employed for moving the pad in the required course, but I prefer and have shown herein a work feed and reset mechanism

similar to that of my application, Serial No. 577,789, for work feed for sewing machine, filed July 27, 1922, which shows a feeding mechanism for a pad of the same form as that for which the mechanism illustrated herein is intended. In the structure of the application referred to, the stitching is arranged at a distance inwardly from the edge of the pad instead of at the edge of the pad, as in the present invention, and the feeding mechanism of said application would merely have to be arranged to operate in a slightly larger path to afford the movement of the pad which is required in the present structure.

Referring now to the drawings, the reference numeral 1 indicates a bed plate of a standard sewing machine, 2 the arm thereof and 3 the head, the latter carrying the usual reciprocable shaft or needle bar 4, carrying the needle 5 which is detachably secured in a socket 6 at the lower end of the shaft or bar 4 by the set screw 7. The shuttle shaft 8 extends under the bed plate 1 in the usual manner, and carries the shuttle 9 which co-operates with the needle in forming the stitches.

Mounted on the bed plate 1 are a pair of guides 10 which engage the lateral edges of a carriage 11, so that the latter is movable in a direction from front to rear of the machine, and this carriage has a pair of spaced guides 12 arranged at right angles to the guides 10 and engaging a frame 13, which is thus confined to move from side to side of the machine or at right angles to the direction of movement of the carriage 11 as clearly shown in my prior application above referred to. The frame 13 is formed with an opening which is internally toothed as indicated at 14, and of a form corresponding to the form of the pad 15 which is to be stitched. These teeth 14 are engaged by a pinion 16 on the vertical shaft 17, which has a worm wheel 18 thereon driven by the worm 19 on the shuttle shaft, so that when the machine is operated, the pinion 16 is rotated, and through its engagement with the internal teeth 14 of the frame 13 impels said frame in a course corresponding to the form of the pad 15, the universal mounting of the frame 13 in the guides 10 and 12, readily permitting the required movement of the frame 13. A cover plate 20 is secured to the top of the frame 13, and has a cam 21 on the under side which engages an axial projection 22 of the pinion 16 or its shaft 17 for holding the pinion in mesh with the internal teeth 14 of the opening in the frame 13.

Referring now to the mechanism for holding the pad, the numeral 23 indicates a yoke which has a bracket 24 attached thereto by the screws 25 and connected by the screws 26 to a bracket 27, which latter is secured by

the screws 28 to the movable frame 13, a spacer 29 being interposed between the brackets 24 and 27 on the screws 26 so as to position the yoke 23 close to and parallel with the upper surface of the bed 1 of the machine, the latter being preferably provided with a surface plate A having a smooth finished top over which the holder and pad may readily slide. A comparatively thin plate 30 is interposed between the yoke 23 and the bed plate 1, so that said plate is held snugly against the upper surface of the plate A and yet permitted to slide between the plate A and the retaining yoke 23, the latter being provided with fingers 31 which project over the lateral edges of said plate 30, and there is a frame 32 secured onto the upper surface of the plate 30 by pins 33 or other suitable fasteners and engaged between the fingers 31, so that the latter serve as guides to control the sliding movement of the frame 32 and plate 30. The frame 32 is provided with an opening 34 therethrough corresponding to the form of the pad 15 which is to be stitched, and the plate 30 is likewise cut away so that the pad 15 fits within the opening 34 and rests directly on the upper surface of the plate A. The frame 32 is also cut away as indicated at 35, but not the plate 30, so as to provide seats for the fasteners 36 which are to be stitched onto the pad 15. Inasmuch as the plate 30 is not cut away to correspond with the openings 35, the fasteners, when placed in the openings 35, rest upon the plate 30.

In those supporters of the type for which the illustrated embodiment of my invention is designed, it is customary to make them in pairs of rights and lefts, and a strip 37 of elastic is secured at one or the other ends of the pad 15, depending on whether the supporter is a right or left supporter. To permit either arrangement the frame 32 is constructed at each end with a shallow recess 38 to receive the end of the strip 37 of elastic in proper position for connection with the end of the pad 15. A spring finger 39 is secured to the frame 32 as indicated at 40 at the inner side of each groove 38, and projects part way across the groove 38 as shown, the end thereof being upturned as indicated at 41, so that the strip 37 of elastic may be inserted thereunder, and the spring finger 39 is arranged to press upon the strip 37 sufficiently to hold said strip in place in the groove 38.

A cover plate 42 corresponding substantially in form to the holder plate 32 is hinged at 43 to the inner edge of the latter, and has an opening 44 corresponding to the opening 34 of the holder plate 32. This cover plate, however, is not cut away above the seats 35, but is provided with apertures 45 located so as to engage the buttons 46 of the fasteners 36, which buttons project

somewhat above the pockets 35, and said apertures are preferably beveled as indicated by dotted lines at 47 in Figs. 2 and 3, so that when the cover plate is closed down 5 against the holder plate 32, the apertures 45 not only readily engage the buttons 46, but by reason of the beveled formation of the apertures, serve to center the buttons and thereby adjust the fastener 36 to the 10 proper position in the seat 35.

A pair of arms 48, preferably formed as a part of the plate 27, project respectively over the opposite ends of the pad holding frame as indicated in Figs. 1 and 2, and 15 each has a vertical slot 49 at the end which is engaged by a lateral projection 50 at the upper end of the post 51, one of these posts being secured at each end of the cover plate 42 to an extension 52 thereof.

20 A pair of spring arms 53 are secured to the inner ends of the arms 48 and at the outer ends engaged over the upper ends of the posts 51 as shown in Figs. 1 and 2, so as to exert a tension downwardly on the 25 upper ends of said posts for forcing the projections 50 downwardly in the slots 49, and when the cover plate 42 is closed down in the position shown in Fig. 2, these springs serve to hold said cover plate in close contact with the holder plate 32. The cover plate is further held in the closed position by a spring latch 54', which is adapted to engage the inner edge of a finger hold 55, which is secured to the outer edge of the 30 cover plate 42.

With this construction which I have just described, it will be observed that the pivotal axis of the projections 50, while capable of vertical shifting, is held by the arms 48 40 against lateral movement, and the axis of the hinged connection 43, (which axis in the closed position of the cover plate 42, is spaced laterally at the inner side of the axis of the projections 50) moves outwardly under the pivotal axis of the projections 50 45 to the outer sides thereof, as the cover plate 42 is raised, the holder plates 30 and 32 being thus slid outwardly, during the raising operation of the cover plate 42, along the surface of the bed plate 1 and between the holding fingers 31, owing to the hinged connection 43 of the cover plate 42 therewith. With this construction the springs 53 not only afford a yielding pressure to hold the 50 cover plate 42 closed, but when the axis of the hinges 43 passes outwardly beyond the axis of the pins 50 also serve to throw the cover plate 42 upwardly and hold the cover plate in the upraised position.

60 It is not only necessary to hold the pad down in the holder 30-32 snugly against the upper surface of the bed plate 1 but it must be engaged close along the line of the stitching, so that the material of the pad 65 will be prevented from lifting as the needle

is withdrawn during the operation of stitching, and, furthermore, as the stitching is applied close to the edge of the pad, it is not practicable to apply holding means to the pad outside the line of stitching. This presents an unusual difficulty, in view of the fact that the stitching is required to extend entirely around the pad and necessitates supporting of the pad clamping means in such a manner that an unobstructed path is af- 70

fording for the needle entirely around the pad. To accomplish this result, I have provided what may be termed a floating presser plate which is carried on the cover plate 42 by members which are withdrawn from the path of the needle as the latter advances around the edge of the pad. The presser plate which is indicated at 54, corresponds in form to the opening 44 which it enters to clamp the pad in place, but is of a smaller 80 size to provide a narrow channel 55' between the edge of the opening 44 of the cover plate 42 and the marginal edge of the presser plate 54 along which the needle operates in stitching the edge of the pad. Rotatable spiders 85 are employed for supporting the presser plate, two of them, as indicated at 56 and 57, being employed in the present structure, owing to the elongated form of the presser plate, which are pivoted at 72 to the presser plate adjacent the opposite ends thereof, and these spiders have the extremities of their arms engaged in sector shape guides 58 on the cover plate 42, said guides being arranged so that a sufficient number of the 90 arms of the spiders are engaged therewith at all times to maintain the presser plate in a fixed position with reference to the cover plate 42. These guides, it will be observed, form substantially circular guide- 95 ways which are interrupted at the intersection of the two circular sections and also at the corners of the pads. This latter may be avoided by enlarging the circles formed by the guides so as to clear the corners but as 100 this is not essential for the satisfactory operation of the device and as it renders it possible to construct the mechanism in a compact form, I prefer with the present form of pad to use circular guides of the smaller circular 105 form. Each arm of the spider is formed on the upper surface adjacent the outer edge with a rib 59, and the usual presser foot of the machine is replaced by a ring 60 which encircles the needle, said ring being main- 110 tained at a fixed elevation just above the upper surface of the spider arms so that it will engage the ribs 59 on the spider arms. With this arrangement, as the machine is 115 turned and the pad holder 30-32 advanced by the hereinbefore described feeding mechanism in a path corresponding to the channel 55', the spider arms which extend across the channel 55' are moved out of the way, as 120 the needle advances, by the engagement of 125

130

the ring 60 with the rib 59 which is just in advance of the needle, the one or the other of the spiders 56 or 57, as the case may be, being rotated on its respective pivot 72 with 5 the outer ends of the spider arms merely sliding along the guides 58 without altering the position of the presser plate 54. With the double spider construction shown, it will be apparent that only one of the spiders is 10 operated at a time, and as the work progresses, the ring 60 passes from engagement with one of the spiders into engagement with an arm of the other spider, and it is necessary that the arms of the spiders must be 15 arranged in proper position for the ring 60 to engage properly against a rib 59 as it passes from engagement with one spider to engagement with the other. I have, therefore, designed the present structure so that 20 the passage of the ring 60 from one spider to the other leaves the spiders as shown in Figs. 2 and 3, with an arm of each spider in line with or end to end with a corresponding arm of the other spider and said arms located midway between the two sides of the 25 channel 44, as this insures a positioning of the next arm with which the ring 60 is to be engaged, so that said ring will properly engage the rib 59 of said arm.

30 In order to avoid displacement of either spider when the ring 60 is not engaged therewith and to insure that the spider which is to be subsequently engaged by the ring will be maintained in position for proper engagement by the latter, I have provided a locking device consisting of a latch member 61 which is pivoted to the cover plate 42 at 35 62 and provided with a notch 63 at each end to alternately engage corresponding ribs 59 of the spiders 56 and 57 when the latter are in the proper inoperative position. An operating member 64 for the latch 61 is pivoted on the bracket 24 at 65 and has a point or finger 66 engaging with a notch 67 in the 40 latch member 61 and is provided with an arcuate slot 68 which embraces the spacer 29 to permit the required pivotal movement thereof for adjusting the locking member 61 to either of the two locking positions. A pair of springs 69 and 70 are connected to 45 the outer extremity of the member 64 and extend respectively in substantially opposite directions therefrom and have their remote ends connected to a fixed part on the sewing machine base 1, as for example, to the opposite ends of the nearest stationary guide 10. These springs are so arranged that when 50 the work holder 30-32 is midway between the limits of its endwise movement (that is from front to the rear end of the machine), the tension of the two springs 69 and 70 is the same, and the operating member 64 is 55 adjusted thereby to intermediate position and shifts the latch member 61 to a corresponding position wherein the end seats 63

are both disengaged from the ribs 59 of the two spiders. This is the position occupied by the pad holding frame as the latter is in position with the needle 5 midway between the ends of the pad, and as the ring 60 passes 70 from engagement with one spider into engagement with the other. In view of the fixed connection of the outer ends of the springs 69 and 70, it occurs that as the pad holding frame continues to advance, the tension on one of the springs is relaxed and the other is increased and throws the operating member 64 in the proper direction to shift the latch member 61 so that one of the notches 63 thereof engages with a rib 59 of 80 the spider which has just been disengaged from the ring 60, and this operation at the same time holds the other notch 63 entirely disengaged from the rib 59 of the spider with which the ring 60 is coming into engagement.

85 The presser member 54 may be constructed in any desired manner, but I prefer to provide same with a depending annular rim 71 as shown in Figs. 7 and 8, as this insures a 90 more effective pressure on the pad where it is needed, that is, immediately adjacent the line of stitching, and it also holds the plate 54 at an elevation to afford convenient connection of the pivot pins 72 of the spiders 95 with the plate.

95 In the progress of the stitching around the pad, there are places where the needle crosses over the thread leading to the stitch which is being formed, and I have found 100 that an exceedingly sharp needle will occasionally puncture the thread and thus interfere with the satisfactory operation of the device. To avoid such interference, the needle is preferably blunted very slightly so 105 that it does not puncture the thread but deflects same at one side or the other of the needle, and I have found that this is an effective precaution and does not detract from satisfactory stitching operation of the needle.

110 In sewing pads of the character for which this invention is designed, it is customary to start the stitching at the same place on all the pads and to overlap the beginning and end portions of the stitching as indicated at 115 73 in Fig. 4, the stitching being begun at the point indicated at 74 in said figure. For the purpose of permitting the overlapping of the stitching and to reset the device at the desired starting position at the completion 120 of the stitching operation, I provide a resetting mechanism of substantially the same form as that shown in my application, Serial No. 577,789 hereinbefore referred to. This mechanism comprises a shiftable clutch member 75 on the shaft 17 which is movable downwardly against the tension of the spring 76 to disengage the shaft and pinion 16 from the driving worm wheel 18, so that the pad holding frame may be freely shifted along 125 130

its course of movement. A bell crank lever 77 is pivoted on the bed plate 1 to engage a roller 78 on the carriage 11 and is connected by a link 79 to operate in the same manner as 5 in the structure of my application above referred to, so that after the overlapping of the stitching has been completed at the point indicated at 80 or at any place between the point 80 and the point 74, the release of the 10 clutch 75 and depressing of the link 79 operates the bell crank 77 against the roller 78 and forces the carriage 11 toward the front of the machine, thereby shifting the pad holder frame to the position wherein the 15 point 74 is directly under the needle 5.

The mechanism for operating the bell crank 77 and clutch 75 is slightly different from that illustrated in my application above referred to and comprises an arm 81 20 which is pivoted at one end to a bracket 82 depending from the bed plate 1 and having the other end connected to the link 79. This arm which is normally held in the upraised position by the spring 83 has a link 84 connected to a pedal or knee operated member whereby the arm 84 is pulled downwardly at the desired time. A clutch shifter 85 in the form of a bell crank, pivoted at 86, engages the circumferential groove 87 of the 25 clutch 75 and has a depending arm 88 engaged by a roller 89 on the pivoted arm 81. The edge of the arm 88 engaged by the roller 89 is suitably formed with an elevation 90 so that the initial operation of the lever 81 30 shifts the clutch shifter 85 to disengage the clutch 75 from the worm wheel 18, the edge of said arm 88 beyond the rise 90 being suitably formed so as to merely hold the clutch 75 disengaged upon further movement of 40 the pivoted arm 81.

In using this machine, the pads 15 are first prepared in two sections ready for stitching, one of which, hereinafter referred to as the outer section, consists of a piece of stiffening 45 material of a form corresponding to the pad and having the outer covering laid thereover with the edges turned in over the stiffening member and pressed so as to remain in the inturned position. The other or 50 inner section comprises an inner covering or lining which likewise has the edges turned in and pressed. These parts are furnished to the operator of the present machine in the form just described, together with fasteners 36 and strips 37 of the elastic. The 55 cover plate 42 is raised to the position shown in Fig. 1, which positions the pad holder beyond the end of the machine so that it is conveniently accessible, and an inner section 60 of the pad is laid in the opening 34 of the pad holder. A pair of fasteners 36 are placed in the seats 35 as shown and these have fabric ends which project inwardly 65 over the section which has been placed in the opening 34. A strip of elastic 37 is then

placed in one or the other of the seats 38, depending on whether the hose supporter is right or left, and projects inwardly a short distance over the section in the opening 34, the spring 39 serving to hold it in place. 70 The outer section of the pad is then placed in the opening 34 and the cover 42 closed down and secured in the closed position by the fastener 54'. As the cover is closed down, the beveled openings 45 of the cover plate engage the buttons 46 of the fasteners 36 and serve to properly position the fasteners 36, and the marginal flange 71 clamps the entire pad securely in the holder. The operation of closing the cover 42 slides the pad holder inwardly so that the point 74 of the pad at which the stitching is to be commenced is directly under the position of the upraised needle 5. The machine is then started, and the pad holder automatically 80 moves the pad so as to form a line of stitching entirely around and close to the edge of the pad, the ring 60 being engaged by a rib 59 of one of the arms of the spider 57 so that the latter turns to afford an unobstructed course for the advancing needle. During the first part of the stitching operation, the locking member 61 is disengaged from the spider 57 so that it is free to turn, but is engaged with the spider 56 so that the 85 latter is held against turning movement until the pad holder moves to a position such as shown in Fig. 3, wherein the ring 60 passes from engagement with the spider 56, whereupon the locking member 61 is reversed and 90 locks the spider 57 and releases the spider 56. Further operation of the machine then causes a turning movement of the spider 56 as the machine continues around one end of the pad, said spider being caused to make 95 almost a complete revolution, whereupon the spider 56 is disengaged from the ring 60 and automatically locked by the member 61 and the ring 60 again engages the spider 57 as the stitching at the other end of the pad is 100 completed. The stitching is continued after it has reached the point 74 down to or part way down to the point 80 so as to overlap the stitching at the beginning and end of the operation. After the stitching has been 105 sufficiently overlapped, the machine is stopped, with the needle in the upraised position and the link 84 operated so as to pull down on the pivot arm 81, and the pad holder is thereby shifted backwardly along 110 the line of stitching 73 to the starting point 74. The fasteners 36 and strip 37 of elastic are now stitched securely onto the pad and upon lifting the cover plate 42 the assembled pad is readily removed and ready for the 115 final stitching along the line 91 which is accomplished by the machine of my other application, Serial No. 577,789.

The present machine being designed to stitch an elongated pad having enlarged 120

ends, preferably employs a pair of spiders having six arms each, as this is found to be a satisfactory structure for this particular form of pad. The present machine, however, is merely illustrative and the invention is not limited to the use of the two spiders with six arms, but contemplates any form or number of spiders or holders whereby a floating plate or presser member is mounted to hold to a pad during the stitching operation so as to afford a clear path around the holder or presser member for stitching the pad.

While I have shown and described my invention in a preferred form, I am aware that various changes and modifications may be made without departing from the principles of my invention, the scope of which is to be determined by the appended claims.

I claim as my invention:

1. The combination with a sewing machine, of a work holder, shiftable supports for the work holder actuated during the stitching operation to afford an uninterrupted path for the stitching, and means operable automatically to lock the shiftable members against operation.
2. The combination with a sewing machine, of a pad holder movable to and from the stitching position, and pad clamping means on the holder the clamping and releasing operations of which serve to shift the holder to and from the stitching position.
3. The combination with a sewing machine; of a work holder, rotatable supports for the work holder actuated during the stitching operation to afford an uninterrupted path for the stitching, and means operable automatically to lock the rotatable members against operation.
4. The combination with a sewing machine; of a pad holder movable to and from the stitching position, and releasable pad clamping means on the holder, and the clamping and releasing operations of which serve to shift the holder to and from the stitching position.
5. The combination with a stitching mechanism for sewing machines; of a work holder operable to move the work relatively to the stitching mechanism with a constant angular relationship to said stitching mechanism so as to apply a line of stitching to the edges of the work, said holder including a presser member engaging the work within its edges, and shiftable supporting means pivoted thereon and adapted to be moved from the path of the stitching

mechanism whereby the entire edge of the article may be stitched by the stitching mechanism.

6. The combination with a stitching mechanism for sewing machines; of a work holder operable to move the work relatively to the stitching mechanism with a constant angular relationship to said stitching mechanism so as to apply a line of stitching to the edges of the work, said holder including a presser member engaging the work within its edges, and a shiftable supporting member pivoted on the holder and having portions extending over the edges of the work and adapted to be moved so that the portions extending over said edges of the work will follow the needle of the stitching mechanism whereby the entire edge of the work may be stitched by said mechanism.

7. The combination with a stitching mechanism for sewing machines; of a work holder operable to move the work so as to apply a line of stitching to the edge of the work along a predetermined course, said holder including a presser member having pivotally supported thereon a shiftable means adapted to be moved from the path of the stitching mechanism whereby the entire edge of the article may be stitched by said mechanism.

8. The combination with a sewing machine; of a pad holder shiftable to and from the stitching position, and pad clamping means pivoted to the pad holder and movable to open and closed positions, and a spring pressing on said pad clamping means whereby when said pad clamping means is closed its pivotal connection is at one side of the line of pressure of said spring, and when open at the other side of the line of pressure of said spring.

9. The combination with a sewing machine; of pad feeding means, a pad holder slidably carried by said pad feeding means and shiftable to and from the stitching position, and pad clamping means pivoted to the pad holder and movable to open and closed positions, said pad clamping means having a shiftable pivotal connection with said pad holder, and a spring pressing on said pad clamping means at said shiftable pivotal connection whereby when said pad clamping means is closed its pivotal connection to said holder is at one side of the line of pressure of said spring, and when open at the other side of the line of pressure of said spring.

WILBUR H. FISHER.
